UNITED STATES PATENT OFFICE

HARALD STAVÖSTRAND, OF OSLO, NORWAY

RELAY

Application filed August 17, 1927, Serial No. 213,612, and in Norway August 20, 1926.

The relay which is the matter of the present application for patent is designed more particularly for use in telegraphic service and to work by influence of weak direct 5 current.

The object stated is attained by means of a novel combination and arrangements of parts to be hereinafter described and claimed and in order that the same may be better 10 understood reference is had to the accompanying drawing forming a part of this specification and showing a side view of the improved relay.

In the drawing 1, 2 designate the coils of a 15 pair of electromagnets, 3, 4 cores of soft iron belonging to the same, and 5, 6 designate pole pieces. 7 is a permanent magnet energizing permanently the cores 3, 4.

The armature 8 of the electromagnets is 20 provided with a projecting sharp edge 9 by means of which it rests on the pole piece 6 of the electromagnet 2 so as to be tilted on the same. The armature is supported by a leaf spring 10 which is secured to a wire 11 25 connected to a screw 12. The latter may be adjusted axially by means of the nut 13 so as to control the tension of the spring 10 and the pressure of the anchor against the pole piece 6.

30 14 designates an arm secured to the armature 8 and provided with contact pieces arranged in well known manner so as to make contact with one or another of the fixed contacts 15 and 16.

35 It will be understood that the armature is permanently kept in place by the energized cores 3, 4. Instead of using a permanent magnet for such purposes a special electromagnet may be used or a special energizing 40 coil as it will be easily understood by all skilled in the art.

In order to obtain a rapid action of the relay the weight of the armature may be reduced to a minimum. The usual friction 45 force in the bearing is in this case avoided by replacing the usual journal bearing of the armature with the said tilting edge.

Owing to the fact that the iron cores are 50 permanently energized the advantages are obtained that the relay may also work by

double current, that it works upon the most favourable part (the steepest portion) of the magnetic curve; that the armature owing to the greater tension of feather is moved more rapidly and may consequently be used for greater telegraphing speed than usual direct current relays. 55

When transferring the motions of the armature to an undulating needle the device 60 may also be used as an undulator for recording vibratory motions of the anchor.

Claims:

1. A relay of the class described, comprising a magnetized horseshoe magnet having pole pieces and also provided with coils having soft cores united to the arms of the magnet, an armature having a pivoting edge bearing against one of the pole pieces, an arm secured to and extending from the armature in one direction and provided at the 65 free end with contacts, spaced fixed contacts between which said contacts of said arm operate, a spring arm extending from the armature in the opposite direction and supporting and tensioning means for the free 70 end of said spring arm.

2. In a relay, a pair of electromagnets, each having a coil and a soft iron core, means for permanently energizing the same, a smooth pole-piece, an armature having a sharp tilting edge contacting with the pole-piece and means for supporting the armature. 8

3. In a relay, a pair of electromagnets each having a coil and a soft iron core, means for permanently energizing the same, a smooth pole-piece, an armature having a sharp tilting edge contacting with the pole-piece, a supporting leaf spring, means for regulating the tension of the spring and contacts coacting with a contact tongue on the armature. 8

In witness whereof I affix my signature.

HARALD STAVÖSTRAND.
